(57) **CLAIM**

The ornamental design for a plumbing snake handle, as shown and described.

DESCRIPTION

FIG. 1 is a first perspective view of a plumbing snake handle showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a second perspective view thereof; and,

FIG. 9 is a third perspective view thereof shown in use.

The broken lines on the drawings are shown for illustrative purposes only and form no part of the claimed design.
